(57) **CLAIM**

We claim the ornamental design for an audio device with display, as shown and described.

DESCRIPTION

FIG. 1 is a front perspective view of an audio device with display showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 2;

FIG. 11 is right-side view thereof in a tilted configuration;

FIG. 12 is a front perspective view of the audio device with display shown in an alternate position in which the display is moved upward;

FIG. 13 is a front view thereof;

FIG. 14 is a rear view thereof;

FIG. 15 is a left-side view thereof;

FIG. 16 is a right-side view thereof;

FIG. 17 is a top view thereof;

FIG. 18 is a bottom view thereof;

FIG. 19 is a rear perspective view thereof;

FIG. 20 is an enlarged view of the encircled portion 20 in FIG. 12;

FIG. 21 is an enlarged view of the encircled portion 21 in FIG. 13;

FIG. 22 is right-side view thereof in a tilted configuration;

FIG. 23 is a front perspective view of the audio device with display shown in another alternate position in which the display is rotated;

FIG. 24 is a front view thereof;

FIG. 25 is a rear view thereof;

FIG. 26 is a left-side view thereof;

FIG. 27 is a right-side view thereof;

FIG. 28 is a top view thereof;

FIG. 29 is a bottom view thereof;

FIG. 30 is a rear perspective view thereof;

FIG. 31 is an enlarged view of the encircled portion 31 in FIG. 23;

FIG. 32 is an enlarged view of the encircled portion 32 in FIG. 24;

FIG. 33 is right-side view thereof in a tilted configuration;

FIG. 34 is an enlarged view of the encircled portion 34 in FIG. 8;

FIG. 35 is an enlarged view of the encircled portion 35 in FIG. 14;

FIG. 36 is an enlarged view of the encircled portion 36 in FIG. 19;

FIG. 37 is an enlarged view of the encircled portion 37 in FIG. 25; and,

FIG. 38 is an enlarged view of the encircled portion 38 in FIG. 30.

The evenly-dashed broken lines in the figures depict portions of the audio device with display which form no part of the claimed design.

The dot-dash broken lines in the figures represent boundaries of the claimed design and form no part thereof.

The dot-dot-dash broken lines encircling portions of the claimed design that are illustrated in enlargements form no part of the claimed design.
